UNITED STATES PATENT OFFICE

2,579,254

TICKET PRINTING AND ISSUING MACHINE

Harold Francis Ford, Cirencester, England, assignor to T. I. M. (Ticket-Issue Machines) Limited, Cirencester, England, a British company

Application August 11, 1949, Serial No. 109,687
In Great Britain September 23, 1947

1 Claim. (Cl. 101—66)

1

This invention relates to portable ticket printing and issuing machines of the kind used, for example, on passenger vehicles to print indications such as the value, class, stage and serial number on a strip of paper drawn from a supply roll within the machine to form a ticket which is ejected after printing, separated from the strip, and handed to the passenger. Examples of machines to which the present invention is applicable are shown and described in United States Patents Nos. 1,920,085 and 2,137,915. In practice the matter printed by these machines has to be varied to suit particular local requirements and in certain instances the range of printed data is less than in others.

The object of the present invention is to provide an attachment applicable to machines of the general character described in the preceding paragraph which is designed to enable the manufacturer of a standard type of machine to introduce variations in the range of printed data as and where required and without entailing structural modifications in the general lay-out of the machine.

According to the invention an attachment is provided for application to a ticket printing and issuing machine of the kind above described said attachment including an adjusting and indicating device applicable to the exterior of the machine and adapted to be brought into and out of operative relationship with a printing die mounted in a rotary printing element and arranged to transmit movement to counting or recording mechanism under certain conditions and in pre-defined positions.

According to one form of the invention means for adjusting a printing die in a ticket printing and issuing machine comprise a hand operated element, means preventing rotational movement of said element until axial travel under hand operation has been completed, clutch elements for transmitting rotational adjustment to a printing die, and rotational means for preventing any movement of the hand operated element during the printing operation.

Reference will now be made to the accompanying drawings which show an arrangement constructed according to the invention and in which:

Fig. 1 is an elevation of a class indication adjustment device applied to a ticket printing and issuing machine,

Fig. 2 is a plan of the device shown in Fig. 1, and

Figs. 3, 4 and 5 are cross-sectional views taken respectively on the lines A—B, C—D, and E—F of Fig. 1.

In the construction illustrated and referring first to Figs. 1 and 2, the device comprises a housing 1 attached to the exterior of the casing

2 of a ticket printing and issuing machine and containing setting and indicating components whose movement is transmitted to a second component disposed within the casing 2 and forming part of a rotary printing element indicated at 3.

The housing 1 is cylindrical and is formed with a flange 4 at one end to provide a means of attachment to the casing 2. In the open outer end of the housing is disposed a knob 5 fixed on a spindle 6 mounted in a bearing 7 within the housing and having mounted thereon a drum 8 bearing on its surface class indications to cover "workmen's," "child's," "return," or other kinds of tickets, the indications being, for convenience, initial letters, one of which is visible at a time through a window 9 provided in the wall of the housing 1. The drum 8 is mounted so as to rotate with the spindle which, however, can move axially through the drum. The inner end of the spindle 6 carries a perforated disc 10 (Fig. 3) one of whose perforations normally engages over a pin 11 fixed in the housing which prevents rotation of the spindle 6 and drum 8 but permits axial movement thereof by pressure applied to the knob 5 against the resistance of a spring 12 surrounding the spindle 6, such movement being limited by a flange 13 on the knob abutting against the outer end of the housing in which position the disc 10 is free from the pin 11 so that the knob, spindle, drum and disc can then be rotationally adjusted.

The inner end of the spindle 6 carries a stem 14 projecting into the interior of the casing 2 and carrying a clutch component 15 adapted to engage a second clutch component 16 mounted on a spindle 17 carried in brackets 18 forming fixed parts of the framework of the printing element 3. The spindle 17 is movable axially against the action of a spring 19 disposed between the clutch component 16 and one of the brackets 18. The spindle 17 also carries between the brackets a rotatably adjustable printing die 20 (Fig. 4) bearing letters or symbols corresponding to those on the indicating drum 8 and arranged to cooperate in printing with non-adjustable dies formed on outwardly turned portions 21 of the brackets 18. The printing die 20 is normally locked against rotational adjustment by a pin 22 on the spindle 17 engaging one of a series of recesses 23 formed in a disc 24 fixed to or formed integral with one of the brackets 18.

To ensure that adjusting movement of the die 20 can take place only when the machine is in the rest or inoperative position, an annulus 25 (Fig. 3) is fixed to the frame members 26 of the printing element 3 and has a partially circular recess 27 in its periphery through which the disc 10 can pass when the knob 5 is pressed inwardly. As the printing element rotates, the

circular edge of the annulus 25 passes partially in front of the disc 10 and prevents the adjusting operation being effected or any alteration made in the setting of the die 20 until a cycle of operations has been completed and a ticket printed and issued.

The pin 22 is carried by a disc 28 (Fig. 5) fixed to the spindle 17, this disc being formed with a flat surface or with flat surfaces 29, according to the classes of tickets which require special recording. The periphery of the disc 28 bears upon an arm 30 pivoted on a rod 31 carried by the brackets 18, the arm being pressed by a spring 32 in a direction to cause its end 33 to engage and operate the ratchet wheel 34 of a counting mechanism as the printing element 3 is rotated around its shaft 35.

The operation of the arrangement above described is as follows:

To adjust the position of the die 20, the knob 5 is pushed inwards of the housing 1 moving the spindle 6 through the drum 8 until the disc 10 is free of the pin 11. The knob is then partially rotated its rotational movement being communicated to the spindle 6 and drum 8 until the 20 indication required appears beneath the window 9. The inward movement of the knob having caused the clutch elements 15 and 16 to engage, the rotational adjustment is transmitted to the die 20. When pressure on the knob 5 is thereafter relaxed, the knob and the disc 10 are restored by the action of the spring 12 to the positions shown in Fig. 1 and the clutch elements 15 and 16 are disengaged. The class printing die having been set and any other necessary adjustments to the printing dies having been made, the printing element 3 is rotated and during its rotation the counting device may be operated. As long as the circular portion of the periphery of the disc 28 is in contact with the arm 30, the arm is held inoperative, but rotational adjustment which brings one of the flats 29 on the disc into contact with the arm allows the spring 32 to move the free end of the arm slightly further away from the axis of rotation of the printing element 3 and into a position to operate the wheel 34 of the counter.

The arrangement above described has been particularly designed for application to existing machines such, for example, as that described in prior Specification No. 1,920,985 or No. 2,137,915, such application enabling a machine to print some additional data or an additional value to meet a special requirement without altering the structure of the machine other than by forming an aperture in the casing through which the spindle of the adjusting component can project.

The improvement according to the invention enables a machine to be easily given an added range of values by including an additional value printing at each operation while another advantage lies in the use of the adjusting device to adapt the machine to indications or abbreviations in a foreign language.

I claim:

In combination with a ticket printing and issuing machine having a walled casing with a printing mechanism therein including a rotatable printing element and actuatable parts for operating the printing element at desired intervals with the printing element in a predetermined position of rest when not in operation, a nonadjustable printing die having spaced apart printing portions mounted on brackets on the

rotatable printing element, a spindle rotatably and endwise movably mounted on said brackets on an axis parallel with the axis of rotation of the printing element, a printing die having optional printing faces around its periphery carried on and rotatable by said spindle between the spaced apart printing portions and having the spindle endwise axially movable therethrough, a clutch part on an end of the spindle adjacent to a wall of the casing, a spring normally resiliently holding said spindle with the clutch end extended, locking means operative when the spindle is thus extended to hold the printing die with a desired printing face in printing position, said casing having an opening through a wall thereof adjacent to and axially aligned with the clutch end of the spindle when the rotatable printing element is in a position of rest, a cylindrical housing secured to the casing and extending outwardly around the opening, a setting spindle endwise movably and rotatably mounted in the cylindrical housing and thus axially aligned with the die carrying spindle when the printing element is in the position of rest, a setting knob fixed on the outer end of the setting spindle, a mating clutch part on the inner end of said setting spindle, a spring normally endwise resiliently retracting said setting spindle to an outwardly extended relation with the mating clutch in a declutched position and yet allowing inward endwise movement to engage said mating clutch with the clutch of the die carrying spindle, said setting spindle carrying indicating markings corresponding to the characters of the printing die, a perforated disc fixed on the inner end of the setting spindle having perforations thereof registering with the setting markings, an annulus carried by the rotatable printing element adjacent to the perforated disc with its peripheral edge overlying and stopping inward movement of the setting spindle, said annulus having a recess at one point in the peripheral edge thereof substantially aligned axially with the die carrying spindle thereby clearing the perforated disc for manual inward movement of the setting spindle to allow engagement of the clutches when the printing element is in the position of rest, and a pin extending from said housing received in a perforation of the disc holding said setting spindle against rotation until the setting spindle is moved endwise inwardly to engage the clutch parts and move the die carrying spindle endwise to release the locking means thereof with the pin entering a perforation of the disc and thus locking the setting spindle against rotation prior to subsequent disengagement of the clutch parts, and said spring then returning the setting spindle endwise outwardly to a declutched position and with the perforated disc withdrawn outwardly through the recess of the annulus to clear the printing element for rotation.
